CLAIM

The ornamental design for a personal mobility vehicle, as shown and described.

DESCRIPTION

FIG. 1 is a front elevational view of a personal mobility vehicle showing my/our new design;

FIG. 2 is a left side elevational view thereof;

FIG. 3 is a right side elevational view thereof;

FIG. 4 is an upper right front perspective view thereof;

FIG. 5 is an upper right rear perspective view thereof; and,

FIG. 6 is a rear elevational view thereof.

The bottom of the vehicle is unornamented and therefore is not illustrated.
